UNITED STATES PATENT OFFICE

169,396

ELECTRIC HEATER

Alexander P. Stirbis and Anthony R. Patrick, Jr.,
Chicago, Ill.

Application October 8, 1952, Serial No. 21,752

Term of patent 14 years

(Cl. D81—10)

To all whom it may concern:

Be it known that we, Alexander P. Stirbis and Anthony R. Patrick, Jr., both citizens of the United States, and residing in the city of Chicago, county of Cook and State of Illinois, have invented a new, original, and ornamental Design for an Electric Heater, of which the following is the specification, reference being had to the accompanying drawing, forming a part thereof.

On the drawing:

Fig. 1 is a front elevational view of an electric heater embodying our new design. The grille is shown only on part of the upper panel but it is to be understood that it continues throughout said panel.

Fig. 2 is an end view thereof.

Fig. 3 is an enlarged cross sectional view with parts broken away taken on a plane indicated by line 3—3 of Fig. 1.

Fig. 4 is an enlarged elevational view of a fragment of the upper portion of said heater.

The rear of the main part of the heater is a plain flat plywood panel extending substantially from one side of the frame to the other side, as partly illustrated in Figs. 2 and 3.

We claim:

The ornamental design for an electric heater, substantially as shown and described.

ALEXANDER P. STIRBIS.
ANTHONY R. PATRICK, JR.
